ROTARY PUMP

John Mann, Seneca Falls, N. Y., assignor to
 Goulds Pumps, Inc., Seneca Falls, N. Y., a
 corporation of New York

Application March 7, 1932. Serial No. 597,232

6 Claims. (CL. 103—5)

This invention relates to certain new and useful improvements in rotary pumps.

Most all rotary pumps usually take the liquid into the rotating element against the opposing 5 centrifugal force set up by the rotation of the gears, cams, pistons or blades. As this force varies with the square of the velocity of the outer part of the cam, gear or blade, it limits the rotative speed of the pump to such a speed that 10 centrifugal force does not entirely prevent filling of part of the tooth spaces. Atmospheric pressure only is available to bring liquid into the suction openings of the pump, and when the rim speed of the gears or blades is high enough to 15 create a centrifugal force equal to the pressure of atmosphere, little or no flow can take place into the suction openings of the rotary pump. This limits the speed at which these pumps can operate, necessitating comparatively low revolutions per minute of the gear or rotor, the 20 operating speed depending upon the diameter of the gears or blades used, so that the resulting centrifugal force does not entirely prevent the filling of the spaces between the teeth of gear 25 or rotor.

Operation of these gear pumps at sufficiently reduced speeds will lower the centrifugal force to such value that the pump tooth spaces will partially fill, but this reduces the volume pumped 30 to less than would be possible if the tooth spaces could fill entirely.

The spaces between the teeth which are receding from the suction opening are only partially filled with liquid, and at the bottom of the tooth 35 spaces a condition of partial vacuum exists.

When these teeth reach the discharge chamber, the pressure existing at this point quickly forces the liquid back into the unfilled spaces, and this sudden filling of the pockets occurs with a 40 distinct impact, giving a noisy condition of operation, increases wear and sets up shocks which are carried through both the pump and piping.

The operation of rotary pumps of the sliding blade type or the piston type is much the same 45 in effect, as with rotary pumps of the gear type.

The main object of the present invention is to provide means of overcoming the centrifugal force set up by the teeth of the gear or the sliding 50 blade or the piston, or rotor of the rotary type of pump which tends to prevent filling of the inlet space in spaces as, for instance, the spaces between the teeth or cams of the pump, causing a reduction from the maximum possible displacement 55 of the rotary pump and limiting the rota-

tive speeds at which they can be effectively operated.

Other objects and advantages relate to the details of the structure and the form and relation of the parts thereof, all as will more fully appear 60 from the following description taken in connection with the accompanying drawings, in which:—

Figure 1 is an elevation of a rotary pump of this invention using an internal ring gear with 65 idler pinion.

Figure 2 is an enlarged section taken on line 2—2, Figure 1.

Figure 3 is a section taken on line 3—3, Figure 2.

Figure 4 is a section taken on line 4—4, Figure 2.

Figure 5 is a section taken on line 5—5, Figure 2.

Figure 6 is a section similar to Figure 2 of a modified form of pump using spur or mangle type 75 gears.

Figure 7 is a section taken on line 7—7, Figure 6.

Figure 8 is a section taken on line 8—8, Figure 6.

Figure 9 is a section taken on line 9—9, Figure 10 illustrating the application of my invention to a piston type rotary pump.

Figure 10 is a section taken on line 10—10, Figure 9.

Figure 11 is a section taken on line 11—11, Figure 12 illustrating the application of my invention to a sliding blade type of rotary pump.

Figure 12 is a section taken on line 12—12, Figure 11.

The self-contained combination constituting the present invention is much the same in general organization, relation and effect regardless of the type of rotary pump involved and for instance, whether the internal ring gear with idler 95 pinion type of pump is used or whether the spur or mangle type gear rotary piston or sliding blade pump is used in that in all these types the rotation of the gears, pistons or blades builds up a centrifugal force which opposes the entrance of 100 the liquid, preventing entire filling of the suction spaces of the rotor resulting in a liquid displacement less than would be possible were the entire suction spaces filled with liquid, limits the operating speed and creates a noisy operating condition because of shock resulting in increased wear, as previously described.

The description of the general operation of one of these types of rotary pump disclosed will 105 therefore constitute in general a description of 110

the operation of this invention as applied to the various types.

Referring to the structure illustrated in Figures 1 to 5 inclusive, there is shown a pump casing 5 consisting of a housing section for containing two axially aligned pumping chambers 2 and 3, the latter of which has one side closed by a closure section 4 secured to the section 1 in any suitable manner, as by bolts 5.

10 This closure section 4 may carry the usual crescent 6 disposed between a portion of the internal gear and the idler pinion. The chamber 3 is preferably of substantially cylindrical form and constitutes the pump chamber of the gear pump, whereas the chamber 2 is preferably of involute form and constitutes the pump chamber of a centrifugal pump.

The inlet for fluid leads through passageway 7 to the chamber 2 and the outlet from chamber 2 20 leads through the passageway 8 to the inlet 3' of the chamber 3, the outlet from chamber 3 being illustrated at 38.

For the purpose of supplying fluid to the inlet 3' of the gear pump at a pressure corresponding 25 substantially with the centrifugal force built up by the gears of the pump there is provided a cylindrical rotor 9 journaled in the wall of the casing 1 which separates the chambers 2 and 3. On the side of the rotor facing the chamber 2 30 it is provided with a series of blades 10 which may be spirally arranged, and as shown are three (3) in number, and may be integrally formed with the rotor and are positioned in the chamber 2 for rotation therein.

35 On the opposite face of the rotor 9 adjacent the chamber 3 there are provided a series of spaced teeth 11 constituting an internal gear substantially fitting the chamber 2 for rotation therein. The idler pinion 12 may be mounted 40 eccentrically on stub shaft 13 projecting inwardly from the closure section 4 for free rotation thereon.

In order to drive the rotor 9 with its blade 45 elements 10 it is mounted centrally upon a shaft 14 extending outwardly through bearing 15 mounted in boss 17 formed on casing 1.

Any suitable packed joint or bearing may be 50 provided for preventing leakage of fluid around shaft 14, as for instance packing 18 backed by sleeve 19 surrounding shaft 14 and pressed against the packing as by means of spring 20 interposed between a shoulder on sleeve 19, and the base of a cap 21 threaded on boss 17.

With this arrangement it will be apparent that 55 two pumps including rotor elements are mounted in a single casing and that the rotor elements are of substantially equal diameters and are driven at the same speed by a single shaft so that the fluid passes from the centrifugal pumping chamber 2 to the gear pump including chamber 3 under substantially the same pressure as the centrifugal force developed by the gear pump so that the fluid is free to enter the inlet 3' of the gear pump under atmospheric pressure.

60 The structure shown in Figures 6 to 8 inclusive differs only in those points essential to adopt the combination to a rotary pump using spur or mangle type gears.

70 In the construction here illustrated by those figures the pump casing is formed of two sections 22 and 23 secured together in any suitable manner, as by bolts 24. In this construction the involute chamber 25 of the centrifugal pump 75 is formed in the casing 23 and the oval chamber

42 of the gear pump is formed between the casing 22 and the wall 26 of the section 23.

In this construction a shaft 27 is journaled in the wall 26 and in the casing section 22 and passes through the chamber 42 of the gear pump 80 and the gear 29 is mounted thereon, preferably for rotation therewith. A second shaft 30 is journaled in the wall 26 and in the casing 22 in substantial parallelism with the shaft 27 and has the gear 31 mounted thereon for rotation therewith and for meshing engagement with the gear 29.

85 As the shaft 30 is the driving shaft it extends outwardly through boss 32 on casing section 22 in the same manner as shaft 14 extends outwardly through boss 17 and may have the same packing construction. Further, shaft 30 projects through the wall 26 of casing section 23 and has mounted thereon an impeller 33 of the centrifugal type and which may include any number of blades 34, as for instance, three, which may be spirally arranged on the face of the impeller disk for rotation within the involute chamber 25.

90 An inlet fitting 35 is provided and secured to the section 23 in any suitable manner as by bolts 36. Liquid is supplied through this inlet to the 100 rotor of the centrifugal pump consisting of the impeller 33 in the involute chamber 25. Liquid is forced by the pump through the outlet 37 from chamber 25 and through conduit illustrated in dotted lines, Figures 6 and 7, to the inlet 39 of 105 the gear pump under the same condition of equalized pressure with the centrifugal force developed by the gear pump as existed with the construction of Figures 1 to 5.

110 Fluid is forced outwardly from the chamber 42 as through outlet 40.

The piston or plunger type of rotary pump as illustrated in Figures 9 and 10 comprises a cylindrical casing 45 having an inlet 46 and outlet 47 for fluid. A rotor 48 is concentrically 115 mounted in the chamber and, as shown, fits tightly within two diametrically opposed sections of the casing periphery as indicated at 49 and 50.

120 Drive shaft 51 extends through the wall of the casing and is connected to the rotor 48 in any suitable manner for driving the same. This rotor, in the usual way, is formed with diametrically extending slots or passageways there-through extending at right angles to each other as indicated at 52.

125 Within these passageways are mounted separate sliding pistons 80 of somewhat lesser length than the diameter of the rotor so that they are capable of sliding within the rotor into and out of substantial contact with the interior wall of 130 the casing. This sliding movement is effected by connecting the pistons to the respective crank arms 53 and 54 as by pins 55 and 56, and these crank arms are mounted on a stub shaft 57 secured in the wall of the casing 45 as, for instance, by nut 58, and as this stub shaft is mounted eccentrically with respect to the drive shaft 51 for the rotor, rotation of the rotor carrying the crank arms and pistons about the stub shaft 57 135 will cause a reciprocation of the pistons in a 140 manner well known.

145 Combined with this type of pump, the feature of this invention resides in the provision of a centrifugal pumping chamber 59 formed within the casing 45, and as shown, the rotor 48 is provided on one of its exterior faces with a plurality of vanes or impeller blades 60 which may be arranged spirally upon the face of the rotor so that the vanes are positioned within the centrifugal pumping chamber 59. Therefore, shaft 150

51 in its rotary movement not only actuates the rotary pumping apparatus, but simultaneously rotates the impeller vanes.

5 The outlet 61 from chamber 59 is connected as by a conduit 70 with the inlet 46 of the rotary pump so that fluid is supplied to said inlet under pressure. With this construction, it will be apparent that the speed of rotation of the rotor is equal to the speed of rotation of the centrifugal pumping device including the impeller blades 60.

10 In Figures 11 and 12, this invention is shown as applied to a sliding blade type of rotary pump. As illustrated, this pump comprises a casing 71 which may be formed in sections if desired secured together in any suitable manner.

15 A slotted rotor 72 is eccentrically mounted within the casing 71 so that its periphery will contact with the inner wall of the casing at one line. A suitable blade or blades 73 is or are slidably mounted in the slot which extends through the rotor. As suggested, this blade may be a single integral blade or the blade may be formed in two sections as illustrated, or any number of blades may be provided either integral or sectional. It 20 is perhaps preferable to form the inner surface or rotor containing chamber within casing 71 in the shape of the well known limaçon curve so that the ends of the blade or blades will always remain in contact with the interior surface of 25 the chamber.

30 In this application of my invention, the eccentric rotor is driven by a shaft 74 extending through the wall of the casing and connected to the rotor in any suitable manner, and with 35 this construction in like manner as the construction shown in Figures 9 and 10, one end surface of the rotor is provided with a plurality of vanes or impeller blades 75 positioned in the centrifugal pumping chamber 76 formed within the casing. 40 The outlet from the centrifugal pumping chamber 76 leads through passageway 77 to the inlet 78 of the rotary pump.

45 An outlet 79 is illustrated leading from the rotary pump chamber while fluid is supplied to the rotary pump in said chamber under the pressure developed by operation of the centrifugal pumping device described.

50 From a consideration of the above, it will be apparent that the disadvantages inherent in the operation of a so-called rotary pump are eliminated in that the fluid is supplied to the suction side of the pump under a pressure substantially equal to the centrifugal force developed by the pumping element or elements of the rotary pump. 55 However, substantial advantages in the operation of such a pump are obtained when the liquid is applied to the suction side of the rotary pump under pressures which may be somewhat less or somewhat greater than the centrifugal force developed by operation of the pump.

60 Further, it will be apparent that the pumping apparatus herein illustrated and described is of a unitary nature in which the driving element of the rotary pump and the impeller of the centrifugal pump are simultaneously rotated by the same means and at the same speed, although variations in this respect are possible.

65 And although I have shown and described specific constructions of pumping apparatus as 70 constituting illustrative embodiments of my in-

vention, I do not desire to restrict myself to the details of form, construction or arrangement, as various changes and modification may be made without departing from the scope of the appended claims.

80 I claim:

1. In a pumping apparatus, the combination of a casing having two chambers therein, of a rotor journaled in the wall between said chambers and provided with impeller blades on one surface in one of said chambers and gear elements on the opposite surface in the other chamber, and means for driving said rotor.

85 2. In a pumping apparatus the combination of a casing having two chambers therein of a 90 rotor journaled in the wall between said chambers and provided with impeller blades on one surface in one of said chambers, and gear elements on the opposite surface in the other chamber, means for driving said rotor, and means 95 connecting the outlet from the chamber including the impeller elements with the inlet to the chamber containing the gear elements.

100 3. In a pumping apparatus, the combination of a casing having two chambers therein, of a shaft journaled in said casing, a rotor positioned between said chambers and mounted on the shaft to be driven by said shaft, said rotor being provided with impeller blades on one surface in 105 one of said chambers, and gear elements on the opposite surface in the other chamber.

110 4. In a pumping apparatus, the combination of a casing having two chambers therein, of a shaft journaled in said casing, a rotor positioned between said chambers and mounted on the shaft 115 to be driven by said shaft, said rotor being provided with impeller blades on one surface in one of said chambers, gear elements on the opposite surface in the other chamber, and means connecting the outlet from one of said chambers with the inlet to the other chamber.

120 5. In a pumping apparatus, the combination of a casing having two chambers therein, of a shaft journaled in said casing, a rotor positioned between said chambers and mounted on the shaft to be driven by said shaft, said rotor being provided with impeller blades on one surface in one of said chambers, and a rotary type of pump mounted on the opposite side in the 125 other chamber, said rotary pump having the driven element thereof mounted to revolve about a fixed axis eccentric to the axis of rotation of said rotor.

130 6. In a pumping apparatus, the combination with a casing having two chambers therein, of a shaft journaled in said casing, a rotor positioned between said chambers and mounted on the shaft to be driven by said shaft, said rotor being provided with impeller blades on one surface in one of said chambers, a rotary type of pump mounted on the opposite side in the other chamber, said rotary pump having the driven element thereof mounted to revolve about a fixed axis eccentric to the axis of rotation of said 135 rotor, and means connecting the outlet from the chamber including the impeller blades with the inlet to the chamber containing said rotary pump.

JOHN MANN.
